UNITED STATES PATENT OFFICE.

MATHEW E. ROTHBERG, OF LEBANON, PENNSYLVANIA.

COKE-OVEN.

SPECIFICATION forming part of Letters Patent No. 718,027, dated January 6, 1903.

Application filed May 14, 1902. Serial No. 107,356. (No model.)

To all whom it may concern:

Be it known that I, MATHEW E. ROTHBERG, a citizen of the United States, and a resident of Lebanon, in the county of Lebanon and State of Pennsylvania, have made a certain new and useful Invention in Coke-Ovens; and I declare the following to be a full, clear, and exact description of the same, such as will enable others skilled in the art to which it applies to make and use the invention, reference being had to the accompanying drawings, and to letters and figures of reference marked thereon, which form a part of this specification.

15 Figure 1 is a half - longitudinal section through a main system of heating-flues and a half-longitudinal section through an oven. Fig. 2 shows vertical sectional views taken on the lines A A and B B, Fig. 1, and also shows 20 an end view of oven and flue. Fig. 3 shows sections taken on the lines C C, D D, E E, and F F, Fig. 1.

The invention relates to horizontal open-end coke-ovens; and it consists in the novel 25 construction and combinations of parts, as hereinafter set forth.

The object of the invention is to provide such ovens with a system of heating or combustion flues whereby it is designed to secure 30 great economy of heat, strength of construction, and rapidity of coking action. The invention is also designed to provide efficiently for regulating and distributing the heat in the different flues, thereby affording means 35 for heating the different parts of the oven-wall at will, and, further, the invention contemplates means for imparting the heat from the waste gases to the air-supply.

The nature of the invention will be clearly 40 understood in connection with the drawings illustrating the same, in which the letter Z designates the coking-chambers of the coke-ovens, and J the hollow wall between the coking-chambers.

45 T represents the top of the ovens, and F the hollow or flue bottom.

The ovens are built in adjacent pairs, as indicated, and the hollow wall between the coking-chambers has its cavity separated into 50 two compartments by a vertical partition D, extending transversely. Each of these compartments is traversed by a vertical revert-

ing-flue consisting of a series of horizontal combustion-flues or heating-flues B, formed by horizontal deflecting - partitions b b, one above another, such flues B communicating at alternate ends in series by the short vertical passage flues e' e' next the partition-wall D and e e next the face-wall G of the oven. The lower end of each vertical series of flues B communicates, by means of the angular flue f, with a horizontal series of transverse reverting-flues C', which extend under the oven-chamber, being in the bottom F. This series of transverse reverting-flues at its outer end communicates with the longitudinal horizontal reverting-flue N, which is under the hollow wall J in the bottom portion of the oven. The transverse reverting - flues are formed in the hollow bottom by the transverse deflecting-partitions c c, in connection with the longitudinal walls m of said bottom, and the longitudinal horizontal reverting-flue N is formed by the long deflecting-partition a.

At or near the termination of the longitudinal flue N in the bottom is provided an opening g for the connection of the valved passage or pipe 1, which extends to the air pipe or flue L, which branches from the hot-air chamber M, which extends around the draft-flue P, through which the waste gases pass to the stack. The pipe 1 is provided with a regulating-valve 2.

The deflecting-partitions b b of the vertical reverting-flue in the hollow wall J are alternately joined to the central partition D and to the face-wall G of the oven. In those which are joined to the face-wall G are provided near such junction in the line of the series of the short flues e e with the valved passages 3. By means of these passages the flues B can be short-circuited, so that the products of combustion can be made to pass directly from one flue B to the next without traversing the length of the flue. The valves 90 are indicated at 4.

The outer ends of each series of reverting-flues C' are provided with an opening 5 through the face-wall for the pipe 6 of the fuel-gas main S, said pipe having a regulating-valve. The heated gases pass through the flues C' and B to the draft-flue P, which is supported above the series of oven-chambers. Heated air to be mixed with the fuel-

gas passes back and forth from the pipe 1 through the reverting-flue N in the bottom to the opening 5.

The outer ends of the flues B are designed 5 to be provided with openings 9 through the face-wall for the purpose of providing means for the direct introduction of both gas and air to said flues B when advisable. Plugs are provided for these openings when they 10 are not in use. By means of these combustion-flues and air-flues the oven-chambers are encompassed in such wise that their heating can be quickly accomplished and easily regulated to suit the work.

15 Having described this invention, what I claim, and desire to secure by Letters Patent, is—

1. In adjacent coke-ovens, a hollow bottom, partitions in the cavity of said bottom and 20 forming transverse reverting combustion-flues, a hollow wall separating the oven-chambers, a transverse partition dividing the cavity of said wall into two compartments, partitions forming longitudinal reverting combustion-flues in said compartments, a reverting hot-air flue leading to said transverse flues, a draft-flue above the ovens, a hot-air chamber surrounding the draft-flue, and sup- 25

plying hot air to said hot-air flue, said longitudinal combustion-flues communicating below with said transverse flues, and above with the draft-flue, substantially as specified. 30

2. In adjacent coke-ovens, a hollow bottom, partitions in the cavity of said bottom and forming transverse reverting combustion-flues, a hollow wall separating the oven-chambers, a transverse partition dividing the cavity of said wall into two compartments, partitions forming longitudinal reverting combustion-flues in said compartments, a reverting hot-air flue leading to said transverse flues, a horizontal draft-flue, a hot-air chamber surrounding said draft-flue, a hot-air pipe communicating with said reverting hot-air flue, and with said hot-air chamber, said longitudinal combustion-flues communicating at one end thereof with said transverse flues, and at the other end thereof, with the draft-flue, substantially as specified. 35 40 45

40 In testimony whereof I affix my signature in presence of two witnesses.

MATHEW E. ROTHBERG.
